SEAL

William Stelzer, Detroit, Mich., assignor to Stof-fel Seals Company, Incorporated, New York, N. Y., a corporation of New York

Application April 3, 1942, Serial No. 437,529

4 Claims. (Cl. 292—310)

The invention relates to seals and more particularly to a press-fastened or press-fastenable seal or tag for cords and the like where the rim of said seal is curled over the cord.

The object of the invention is to provide a one-piece seal of neat appearance that is absolutely tamperproof and that can be manufactured at low cost.

Present seals of the type described are secured to the cord by means of an inward curl which is difficult to produce and requires the use of precision tools.

The present invention aims to eliminate the inward curl without reducing the security or usefulness of the seal in any way by curling the rim of the seal outwardly and to wrap the cord or wire within the rim.

Another object is to produce a novel pre-fabricated shape which necessitates the least effort for fastening of the seal in the field.

The leading object of the invention is to provide a novel seal and a novel method of securing it to a cord or wire so that metal with greater tolerances in thickness and temper may be used, and to conserve metal of a higher grade.

Further aims and advantages will appear by inspection of the drawing, wherein:

Fig. 1 is a sectional side view of the novel seal in the pre-fabricated shape before it is fastened;

Fig. 2, a plan view thereof;

Fig. 3, a sectional side view illustrating the method of fastening the seal.

Fig. 4, a plan view of the finished seal;

Fig. 5, a plan view of a modified construction;

Fig. 6, a sectional side view of the seal corresponding to Fig. 1 but of modified construction.

Fig. 7, a further modification of the seal shown in Fig. 1; and

Fig. 8, a sectional side view showing a modified construction where one side of the seal is curled in the pre-fabricated shape.

In the preferred embodiment, the improved seal or tag in its pre-fabricated shape consists of a cup-shaped member 1, shown in Figs. 1 and 2, having a rim 2 whose lower extremity is curled at 3 to facilitate the press-fastening operation. The rim has two diametrically disposed slots 4 to accommodate the cords or wires 5 shown in the finished seal illustrated in Fig. 4.

2' indicates the rim of the fastened seal in which the cords 5 are locked, shown in section in Fig. 3. A simple curling die 6 is required to close the rim. A punch 7 engages the back of the disc and is moved in the direction of arrow 8, or the die 6 is moved in the direction of arrow 55

9. An injector 10 yieldingly presses against the cup so that the shape of the back is maintained during the fastening operation.

The seal may be made of any suitable metal, but in the preferred embodiment I use enamelled sheet steel, whereby the central areas of both sides of the seal may be used for advertising or utilitarian printing, as illustrated in Fig. 4.

While curl 3 as shown in Fig. 1 provides a cup 10 that is extremely easy to fasten, because the effort required to close the rim is very small, the rim may be only slightly flared out as at 11 in Fig. 6, or not at all as in cup 12 shown in Fig. 7. These modified constructions require a greater pressure 15 for forming the curl, but afford slight simplification in manufacture.

The novel seal is suitable for use with metallic or non-metallic cord, or wire, and it is customary to seal the two ends, whereby one end is held in 20 one half of the rim, and the other end is held in the other half. However, the seal is satisfactory in security and appearance if both ends are placed in the same half of the rim. Where certain wire is used instead of cord it is easier to 25 place both ends in one rim. For this purpose I provide a modified construction shown in Fig. 8 where a cup 1 similar to that shown in Fig. 1 has one half, as indicated by numeral 13, finished in fabrication so that the effort required to fasten 30 the seal to the wire is further reduced.

It is apparent that the invention can be carried out in ways different from that shown, and the outline of the seal may vary to suit the particular purpose for which it is intended, for 35 instance it may be formed as illustrated by seal 14 in Fig. 5.

Various methods of further securing a cord or wire in an inwardly curled rim, consisting of crimps or tabs, are known, and may be incorporated in this construction, however, I have found that a rim firmly curled around a cord holds the latter absolutely secure, so that crimping is of small value unless used only for appearance such as an ornament.

45 I do not wish to be limited in the scope of the invention to these particular embodiments except by the terms of the appended claims.

I claim:

1. A seal consisting of a circular cup shaped member having a marginal rim whose edge is flared outwardly at its extremity to facilitate an outward curl which is to receive the ends of a cord, and diametrically opposed slots to accommodate the ends of said cord, said marginal rim being of such a height that after it is curled it

extends above and below the bottom of said cup shaped member.

2. A seal comprising a prefabricated circular cup whose rim has a pair of diametrically opposed slots to accommodate a fastening member, said rim being divided into two halves by said slots, one half being curled outwardly during pre-fabrication to form a completed curl extending beyond the bottom surface of said cup, the other half being flared outwardly to form the beginning of a curl into which said fastening member is wrapped and which is closed in a press when the seal is to be secured.

3. A sheet metal seal comprising a pre-fabricated circular cup having a bottom and a marginal rim, the marginal extremity of said rim being bent outwardly in the pre-fabrication to form the beginning of an outward annular curl and to facilitate a re-bending operation during

which a fastening member is placed into said curl to be enveloped and secured by said curl while it is closed in said re-bending operation said curl extending on both sides of the bottom of said cup.

4. A sheet metal seal comprising a pre-fabricated circular cup having a bottom surface and a marginal circular rim, and diametrically opposed openings in said rim to provide room for the insertion of a fastening member, the marginal extremity of said rim being bent outwardly in the fabrication process to form the beginning of a curl of said rim and to receive a fastening member to be embedded and locked in said rim in a re-bending operation so that said rim forms a closed annular curl extending on both sides of said bottom surface.

WILLIAM STELZER.
